UNITED STATES PATENT OFFICE.

JOHN M. SCHWENDEMANN, OF DOUGLAS, OKLAHOMA.

AUTOMATIC MAIL-CARRIER.

1,081,409.

Specification of Letters Patent. Patented Dec. 16, 1913.

Application filed September 10, 1913. Serial No. 789,210.

To all whom it may concern:

Be it known that I, JOHN M. SCHWENDEMANN, a citizen of the United States, residing at Douglas, in the county of Garfield and State of Oklahoma, have invented certain new and useful Improvements in Automatic Mail-Carriers, of which the following is a specification, reference being had to the accompanying drawings.

10 This invention comprehends certain new and useful improvements in automatic mail carriers and has for its primary object to provide an automatic mail carrying apparatus which will be especially adapted for 15 use in rural districts.

Another object is to generally improve the construction and operation of carriers of this type and construct the same so that they may be readily employed for carrying the 20 mail between the house and the road, or from the post-office to the patrons' homes.

A further object is to provide a device of this character having a pair of independent motors connected with separate and independent trolley wheels to operate the same, and a shifting mechanism, whereby either motor may be thrown into operation to cause the carrier to travel in the proper direction upon the trolley or cable.

30 A further object is to provide novel shifting or reversing mechanism and a novel form of stop and latch mechanism for a device of this character and to generally improve and simplify the construction and operation of the various parts of the device and increase the efficiency of the same.

With the above and other objects in view, my invention consists in certain novel constructions, combinations, and arrangements 40 of parts to be hereinafter more fully described, claimed, and illustrated in the accompanying drawings, in which,

Figure 1 is an elevational view of my device in position upon one end of the trolley; Fig. 2 is an enlarged longitudinal vertical section through the carrier, with parts broken away for the sake of clearness; Fig. 3 is a transverse vertical section through one end of the apparatus, with parts broken 50 away; Fig. 4 is a horizontal sectional view through one end of the apparatus; Fig. 5 is a detail horizontal sectional view on the line 5—5 of Fig. 3, looking in the direction indicated by the arrow, the car and cable being shown in dotted lines; Fig. 6 is a detail 55 vertical sectional view on the line 6—6

of Fig. 5; Fig. 7 is a vertical transverse sectional view through one end of the device, showing the stop and latch mechanism in operative position, parts being removed in 60 this figure for the sake of clearness; Fig. 8 is a vertical longitudinal section through the end, showing the stop and latch mechanism in operative position; and Fig. 9 is a horizontal sectional view through the apparatus, looking down upon the stop and latch mechanism with the same shown in full lines while only a few of the other parts are shown in dotted lines, for the sake of 65 clearness.

Referring more specifically to the drawings in which similar reference characters designate corresponding parts throughout the several views, 1 designates the car of the apparatus which is preferably of rectangular form with its ends 2 pointed, as clearly shown in Fig. 1, and has a central or main compartment 3 to receive mail matter or the like, and a door 4 for closing said compartment, said door carrying a latch 5 of a suitable form for retaining the door in closed position, it being understood that the door is hinged along one edge, as shown at 6. The car is provided with the vertical partitions 7 to separate the main or central 80 compartment 3 from the end compartments 8 within which are positioned suitable 85 spring motors, as will be presently fully described.

Within each end compartment is a main 90 shaft 9 upon which is mounted a spring 10 and a large gear wheel 11. The large gear wheel 11 is connected by means of an intermediate gear wheel 12 to another gear wheel 13 mounted upon the shaft 14 which also 95 carries a second spring 15. It will be understood that the shafts 9 and 14 rotate in the same direction, under action of their respective springs 10 and 15. It will also be understood that each of the springs is 100 secured by one end to its respective shaft and by its other end to a stationary member secured to the wall of the end compartment 8. The shaft 9 also carries a gear wheel 16 which meshes with the gear wheel 17 mounted on the shaft 18 which also carries a larger gear wheel 19. The gear wheel 19 meshes with a gear wheel 20 mounted upon the stub shaft 21 carried in the upwardly directed plate 22 secured to the upper portion of the 110 outer face of the car 1 and extending longitudinally thereof.

The gear wheel 20 meshes with a gear wheel 23 rigidly mounted upon the shaft 24 which extends through the opposite ends of the U-shaped bracket member 25 and is rotatably mounted therein, it being understood that the U-shaped bracket member 25 forms a continuation of the standard 26 which projects upwardly from the plate 22, directly above the stub shaft 21, one end of the bracket member 25 connecting with the upper end of said standard 26. It will be understood that the gear wheel 23 is mounted upon the shaft 24 near one end of the latter and a spacing collar 27 is loosely mounted upon the shaft between the gear wheel 23 and the pulley or trolley wheel 28 which is loosely mounted upon the shaft 24 and carries the clutch member 29 upon one face which is adapted to be engaged at times by the clutch member 30 keyed to the shaft 24 and having an extended reduced or neck portion 31 upon its outer face with the annular flange or head 32 formed in its outer end and engaged in the lower end of the arm 33 which is loosely mounted upon the shaft 24 and carries the curved finger 34 for engagement at times against the inner face of the outer arm of the U-shaped member 25 to force the cam member 30 into engagement with the cam member 29 and thereby cause the loose pulley or trolley wheel 28 to rotate with the shaft 24 and thereby cause the car 1 to move in the proper direction beneath the cable 35, upon which the pulley or trolley wheel 28 is engaged. It will be understood that the cable 35 is suitably mounted upon the outer ends of the bracket arms 36 secured to and projecting laterally from the posts 37. The central portion of the U-shaped bracket member is supported by the brace rod 38 which has one end connected therewith and its opposite end connected with the plate 22, as will be readily understood by referring to Fig. 2. The upper end of the arm 33 is provided with an elongated longitudinal slot 39 and a pin 40 is engaged through this slot, said pin being carried by one end of the shift rod 41 which has the handle 42 formed upon one end. It will therefore be seen that as there are two arms 33, when the shift rod 41 is in one position, the curved arm 34 carried by one of the arms 33 will be engaged with the inner face of the outer arm of its respective U-shaped bracket member 25, thereby retaining the clutch member 30 in engagement with the clutch member 29 at this end of the device and causing the car to move in the proper direction upon the cable 35. When the shift rod is reversed, however, causing the arms 33 to swing to their opposite positions upon the shafts 24 it will disengage the first curved arm 34 from the bracket member 25 and engage the other arm 34 with its bracket

member 25, thereby withdrawing the first clutch member 30 from engagement with its clutch member 29 and engaging the outer clutch member with its clutch member 29, thereby allowing the car to move in the opposite direction under action of the springs 10 and 15 of the other motor.

In order to stop the car at each end of the cable, I have provided a novel form of stop and latch for each motor. Each stop and latch mechanism comprises a latch bar 43 which is pivoted at one end, as shown at 44, near the pointed end of the compartment 8 and within the same and is provided with the depending pointed latch teeth 45 adapted for engagement in the teeth of the ratchet wheels 11 and 13 to stop operation of the motor when the latch bar swings upon its pivoted end 44 to its lowermost position. The latch bar 43 is connected to the upper end of the rod 46, which has its lower end pivoted to the right angled end 47 of the lever 48 which depends through the opening 49 in the lower wall of the compartment 8, said lever being pivoted in the compartment 90 at its bend, as shown at 50. During operation of the motor, the lever 48 is in the position shown in dotted lines in Fig. 8 and as the car nears the end of the cable or at any other point at which it is desired to stop the car, the lever 48 engages the raised or offset free end 51 of the stop arm 52 secured to one of the posts 37 and extending beneath the car 1 and in the path of the lever 48. This will cause the lever 48 to swing upon its pivot 50 to the position shown in full lines in Fig. 8, causing the rod 46 to draw the latch bar 43 downwardly and engage the teeth 45 thereof with the teeth of the ratchet wheels 11 and 13, as previously 105 stated, thereby stopping operation of the motor. The helical spring 43 which has one end secured to the rod 46, as shown at 54, and its other end fastened to the bracket 55 secured to the lower wall of the compartment 8, serves to retain the latch bar 43 in either raised or lowered position, as will be clearly understood, owing to the upper end 47 of the lever 48 being extended at right angles to the main portion thereof and the 115 lever pivoted at its bend, as shown at 50, as will be clearly apparent by referring to Fig. 8. It will be understood that one motor is held against operation by its latch bar 43 during operation of the other motor and therefore when the second motor is stopped, the car is prevented from moving in either direction. It will also be understood that movement of the lever 48 is limited in either direction by the slot 49 through which the 120 lever extends.

From the foregoing it will be apparent that I have provided an automatic mail carrier which will be highly efficient and effective in use as well as extremely simple in 130

construction and operation. It will be understood, however, that while I have shown the preferred embodiment of my invention, minor changes in the details of construction 5 may be made within the scope of the appended claims without departing from the spirit of my invention or sacrificing any of the advantages of the same.

What I claim is:-

- 10 1. A device of the class described comprising a car, a trolley, a pair of spaced trolley wheels above the opposite ends of the car, means for supporting the wheels in proper position, the opposite ends of the car being pointed and separated from the main portion of the car by partitions, thereby forming a main compartment and end compartments, means for closing the main compartment, a motor within each end 15 compartment, means for suspending the car below the trolley wire, and means for operating either trolley wheel from the motor below the same.
- 20 2. A device of the class described comprising a car having a main compartment and end compartments, a motor within each end compartment, means for closing the main compartment, a trolley wheel above each end compartment, means for supporting the trolley wheels, connections between the trolley wheels and the motors therebeneath, and means for disconnecting either trolley wheel from its motor while the other trolley wheel is connected with its motor.
- 25 3. A device of the class described comprising a car, a trolley wire above the car, means for suspending the car from the trolley wire, means for resiliently retaining the suspending means in normal position, a 30 spring motor within the car, a stop member, means for engagement with the stop member to stop operation of the motor, said stop member projecting through the bottom of the car, a trolley wheel above the car and 35 engaged upon the trolley wire, transmission mechanism between the motor and the trolley wheel, and means for throwing the transmission mechanism out of operation.
- 40 4. A device of the class described comprising a car, a motor in one end of the car, a trolley above the car, a trolley wheel mounted on the trolley, means carried by the car for supporting the trolley wheel, means for operatively connecting the trolley with 45 the motor, means for automatically stopping 50 operation of the motor, means for retaining

the last mentioned means in inoperative position, and means for releasing the motor stopping means.

5. A device of the class described comprising a car, independent motors within the car, a trolley above the car, trolley wheels mounted upon the trolley, means carried by the car for supporting the trolley wheels, connections between the motors and the 60 trolley wheels, means for disconnecting one of the trolley wheels from its motor, stop members projecting from the car, means for resiliently retaining the stop members in position, means for reversing the position of 70 the stop members, and means connected with the stop members for engagement with the motors to stop the same upon reversal of the position of the stop members.

6. A device of the class described comprising a car, a motor within each end of the car, a trolley above the car, a trolley wheel above each end of the car, means for supporting the trolley wheels above the ends 80 of the car, connections between each trolley wheel and the motor therebeneath, means for disconnecting either trolley wheel from its motor, means for stopping operation of either motor, and means for actuating the last mentioned means.

7. A device of the class described comprising a car having a central compartment and end compartments, motors within said end compartments, a trolley above the car, trolley wheels mounted above the opposite 90 ends of the car and connected with the motors in the respective ends of said car, said trolley wheels being engaged upon the trolley, and means for disconnecting either trolley wheel from its motor.

8. A device of the class described comprising a car, motors within said car, a trolley above the car, trolley wheels mounted on the trolley, means carried by the car for supporting the trolley wheels, transmission 100 mechanism between each motor and the adjacent trolley wheel, means for automatically stopping operation of the motor, means for retaining the last mentioned means in inoperative position, and means 105 for releasing the motor stopping means.

In testimony whereof I hereunto affix my signature in the presence of two witnesses.

JOHN M. SCHWENDEMANN.
